UNITED STATES PATENT OFFICE.

CLARENCE R. MILLER, OF FLINT, MICHIGAN.

CARRIAGE-LOCK.

1,065,705.

Specification of Letters Patent. Patented June 24, 1913.

Application filed December 19, 1912. Serial No. 737,669.

To all whom it may concern:

Be it known that I, CLARENCE R. MILLER, a citizen of the United States of America, residing at Flint, in the county of Genesee and State of Michigan, have invented certain new and useful Improvements in Carriage-Locks, of which the following is a specification, reference being had therein to the accompanying drawings.

10 In latching doors in the bodies of automobiles and other vehicles, it is desirable that the parts be held together in such way as to take up any lost motion and to hold the door firmly. It is also necessary to arrange the parts in such manner that they do not catch the wearing apparel of persons using the door.

This invention relates to a carriage lock for holding a vehicle door in closed position and to an arrangement thereof whereby any loose play between the parts is prevented and whereby the operating handles cannot interfere with the passage of persons through the door-way.

25 The invention also provides for application to either right or left hand doors.

The invention consists in the matters hereinafter set forth and particularly pointed out in the appended claims.

30 In the drawings, Figure 1 is a view in transverse section of a door and casing to which a lock that embodies the invention is applied; Fig. 2 is a view, partly in side elevation and partly in section, of the applied lock and adjacent portions of the door and casing, with the line I—I indicating the section on which Fig. 1 is taken; Fig. 3 is a view in section taken on or about line III—III of Fig. 2; Fig. 4 is a view in detail of a latch plate; and Fig. 5 is a view in detail of the lock proper.

As herein indicated a door 1 has a stop 2 or rabbet strip adapted to overlie and close on the outer face of a door jamb 3, the latter preferably being provided with cushioning stops 4. A latch plate 5 is inset in the face of the jamb 3 and has a throat with oppositely beveled or inclined faces 6. Screws 7 or like means hold the latch plate in position.

50 A lock casing is inset in the margin of the door and is provided with outer beveled faces 9 adapted to enter between the corresponding faces 6 of the latch plate. The casing is held in position by screws 10 or the like and is provided with a pair of lugs

11 either one of which, according to the arrangement of the lock on a right or left hand door, is apertured to form a bearing for a pivot screw 12 that passes through the door and the lug opening into the body of the door frame. A latch bar 13 is pivoted on the screw and has a rounded head 14 that is adapted to be projected by a suitably disposed spring 15 against the adjacent face 6 of the latch plate 5 when the door is closed and to snap past the margin of the plate and hold the door shut when the latter is fully home.

The face of the head 14 which engages the marginal portions of the latch plate is so beveled or disposed that it crowds the door inwardly and tends to hold the stop 2 against the yielding cushions 4 and to take up any action due to permanent compression or wear of the stops.

The latch may be thrown by any preferred means, as for example, a link 15 whose inner end portion 16 hooks under the latch plate 13 and whose upper end portion 80 is pivoted to a rock arm 17. A suitable face plate 18 affords a bearing support for the rock arm or push member 17 while the lower end portion 16 of the link travels in the slot indicated at 19 in the casing 9. The plate 85 18 is secured in position by suitable screws 20 or the like while the projecting portion of the push member 17 is so shaped as to present a contour that will not catch the apparel of persons passing through the door. 90

In operation, the parts act as a spring latch when the door is closed to bring the latter into proper alinement with the door jamb and to hold it from rattling. The co-acting beveled faces of the latch plate and latch casing serve to firmly support the outer portion of the door when closed while the latch itself forces the door yieldingly and firmly against whatever stops may be provided. The parts may be applied readily to a door and are practically concealed when so applied and the operating or push member does not impede the passage of persons through the door.

Obviously, changes in the details of construction may be made without departing from the spirit of the invention and I do not care to limit myself to any particular form or arrangement of parts.

What I claim is:—

1. The combination with a swinging door and jamb therefor, of a latch plate inset in

- the jamb, and provided with oppositely inclined bearing faces, a latch casing on the door adapted to enter between the bearing faces of the plate and coact with the latter
- 5 to draw the door to alinement, a spring latch in the casing adapted to engage the plate and draw the door yieldingly inward when the casing is approaching full engagement with the plate, a pivot member extending through a guide opening in the casing and engaging the body of the door on which the latch is pivoted, and a push member projecting from the face of the door and operating the latch.
- 10 2. The combination with a swinging door and jamb therefor, of a latch plate inset in the jamb, and provided with oppositely inclined bearing faces, a latch casing on the door adapted to enter between the bearing
- 15 faces of the plate and coact with the latter
- 20

to draw the door into alinement, a spring latch in the casing adapted to engage the plate and draw the door yieldingly inward when the casing is approaching full engagement with the plate, a pivot member extending through a guide opening in the casing and engaging the body of the door on which the latch is pivoted, a link reciprocable in the body of the door and extending into the latch casing for lifting the latch, 25 and a push member on the door operatively connected to the link for reciprocating the latter.

In testimony whereof I affix my signature in presence of two witnesses.

CLARENCE R. MILLER.
